UNITED STATES PATENT OFFICE

NORMAN P. HARSHBERGER, OF SCARSDALE, NEW YORK, ASSIGNOR TO THE BARRETT COMPANY, OF NEW YORK, N. Y., A CORPORATION OF NEW JERSEY

SHINGLE

Application filed June 5, 1931. Serial No. 542,317.

This invention is directed to shingles and particularly to interlocking composition shingles arranged to lock with other like shingles, forming, when applied to a roof 5 or other surface in successive courses, a definite, pleasing geometrical figure.

One object of this invention is to provide a shingle which can be cut with substantially no waste, and when laid with other like shingles in courses, imparts a decorative geometrical figure to the roof and also results in a waterproof efficient roof covering.

Another object is to provide a shingle having projecting portions and step portions 15 which serve as guides in the application of the shingles in abutting relationship on a roof and also form interlocking means to hold down the forward edges of the overlying shingles and thus improve the weathering 20 properties of the roof or other surfaces to which the shingle elements may be applied.

Other objects and advantages of this invention will appear from the following detailed description.

Individual shingles, the lower edges of which are provided with projecting portions and adapted to engage when laid with slits or slots of subjacent shingles are well known. This invention is in the nature of an improvement 25 on such shingles in that it provides a more durable element and one which can more readily and quickly be applied in interlocking relation. The shingle of this invention is particularly adapted for reroofing 30 purposes but it will be understood that it may be used in the production of new roofs.

This invention comprehends an interlocking shingle, preferably of rectangular shape, having a stepped portion in one side corner 40 of the shingle, a projecting portion in the opposite side corner and an interlocking projection on the lower corner. The stepped portion of one shingle is arranged to abut against the projecting portion or the non-homologous portion of another shingle in the same course and form a slot which is adapted to engage and lock with the interlocking lug of a shingle of an overlying course. In addition to providing a locking means for the interlocking lug, the stepped and projecting por-

tions serve as guides in the laying of the shingles and permit ready and quick application of the elements in even courses so as to obtain the desired geometrical figure.

The structure of the shingle resulting in 55 the formation of a slot between adjacent shingles when laid eliminates the necessity for a slit in the body portion of the shingle to lock down the side edges of the interlocking projection. Such a slit weakens the 60 body portion of the shingle by reason of the break in surfacing and the division of the fibrous base. Therefore its elimination improves the strength, durability and weathering 65 properties of the shingle to a considerable degree.

In the accompanying drawing forming a part of this specification, and showing for the purposes of exemplification, a preferred form of this invention, but without limiting 70 the claimed invention to such an illustrative instance;

Fig. 1 shows a plan view of a shingle illustrating the preferred embodiment of this invention;

Fig. 2 illustrates a fragmentary plan of a number of shingles arranged in courses upon a roof or other surface; and

Fig. 3 is a plan view of a strip of shingle material indicating the manner in which the 80 shingles may be cut from the strip.

In the preferred embodiment illustrated in the drawing, the invention is shown incorporated in a shingle of the parallelogram type which is adapted to be laid in courses 85 with like shingles to give a regular geometrical appearance, and the present description will be confined to the present illustrated embodiment of this invention in such shingles. It will be noted, however, that the 90 novel features and improvements are susceptible of other applications such as to strip shingles and shingles of different shapes. Hence, the scope of this invention is not confined to the embodiment herein described. 95

Referring to Fig. 1 of the drawing, 11 indicates a shingle of substantially rectangular shape constructed in accordance with the teachings of the present invention. In this preferred embodiment the body portion of 100

the shingle is defined by sides 13, 14, 19 and 22, said sides being disposed at right angles to each other.

The lower corner formed between the adjacent sides 13 and 14 is provided with a projecting lug 12, said lug having a bottom edge 23 which is cut on a line substantially parallel to the diagonal connecting the two adjacent opposite side corners of the shingle. 10 The sides of the lug extend vertically for a short distance and are then connected to the sides 13 and 14 by diagonal lines perpendicular to the said sides 13 and 14. By reason of this tapering of the sides of the lug, the locking of the lug with the slot or slit members is facilitated.

The corner of the shingle defined by the adjacent sides 13 and 22 is cut off as at 18 to form a truncated portion having a vertical side. The step 17 which cooperates to 20 form a locking slot in a manner to be presently described, is formed in the side 18 by horizontal cut 24 and a vertical cut 25 which is extended to the side 13.

25 The sides 14 and 19 define the opposite corner of the shingle, the side 19 being left intact in the cutting process. The side 14 is interrupted not only by the lug 12, but also by the slit 16 cut vertically in the body 30 portion of the shingle. The vertical slit 16 in combination with the extended portion 25 define a projection 15 extending downwardly from the body portion of the shingle and terminating on a horizontal edge 26, which 35 runs at an angle to the side 14.

The fourth corner, i. e., the corner defined by the sides 19 and 22 is characterized by a projection 27 formed between side 19 and the vertical cut 28. A horizontal cut 21 in combination with cut 28 provides a stepped portion 40 which is formed incidental to the cutting operation and may be used as a guide in arranging the shingles in courses.

The shingle illustrated in Fig. 1 may be 45 cut from a single sheet of material without substantial waste, as shown in Fig. 3. In the cutting operation two lug portions 12 of diagonally positioned shingles 30, 31 are cut in abutting relation with each other, the 50 stepped portions 17 and the portions 18 of the pair of diagonally positioned shingles 32 and 33 being formed in the cutting of the two lugs 12 on shingles 30 and 31. The projecting portion 15 of shingle 31 is defined by 55 cuts 21 and 28 forming the recess in the upper corner of the shingle 33. By the described method of cutting, the entire sheet of material is utilized, with the exception of the relatively small fragments 34 in the center 60 of the sheet located between the sides 17 and 18 and the projecting lugs 12.

The shingles are preferably made from usual roofing felt saturated and coated with bituminous material and surfaced with granular material in accordance with well estab-

lished roofing practice. The granular material may be of one color or vari-colored, and if desired, opposite surfaces of the shingles may be surfaced with contrasting colored materials.

With reference to Fig. 3, it will be noted 70 that the shingles are adapted to be laid in abutting relationship in successive courses. The alignment of the shingles is secured by matching the projecting portion 15 with the stepped portion 17 of the adjacent shingle. This alignment forms a slot 29 adapted to 75 form a part of the interlocking means. The projecting lug 12 of the shingle of the next highest course is locked by the slot 29, formed 80 as above described and by slit 16 which is cut on the inner side of the projecting portion 15, the ends of lug 12 passing through slots 29 and 16 in the pair of underlying shingles and locked down thereby. By means of 85 this interlocking, the lower edge of the locked shingle is securely fastened and is not susceptible of being warped or turned upwardly by the wind.

It will be noted that by virtue of the 90 interlocking lug 12, the point of abutment of the shingles is completely covered, thus avoiding exposure of the edges to the elements. It will also be noted that the novel construction herein described obviates the use of a 95 locking slit, thus eliminating a cutting step in the manufacture of the shingle, and furnishing a shingle of maximum strength and resistance.

By the use of the projecting portion 15 100 and the stepped portion 17 to form an interlocking slot, an extra layer of material, i. e., the projecting portion 15 lies below the locking lug 12 when the shingles are laid. This produces a regular series of raised or double 105 portions of roofing material at the forward edge of the lugs 12, which give rise to a deep shadow effect, thereby increasing the attractiveness and novel appearance of the roof.

The invention, as herein described, is embodied in the particular form of construction, but it may be variously embodied within 110 the scope of the following claims.

I claim:

1. An interlocking shingle element having 115 an interlocking lug extending from the converging end of two adjacent edges and having a projection on one side edge and a recess beneath the projection, said projection arranged to abut against a second projection on a non-homologous side edge of a like shingle element to form a slot, the opposite sides of which are defined by an outer edge of the second projection and an edge of said recess, said slot arranged to receive 120 and lock with the interlocking lug of another shingle.

2. A roof composed of a plurality of like shingles arranged in courses to form a desired figure, the non-homologous edges of said 125

shingles being laid in substantially abutting relation, each shingle having a projecting portion extending from the intersection of two adjacent edges and a stepped portion extending from the intersection of two opposite adjacent edges, said projecting portion and said stepped portion cooperating to form a slot the opposite sides of which are defined by a side edge of the projecting portion and an inner edge of the stepped portion, and a projecting lug on the lower edge of each shingle arranged to lock in said slot.

3. A roof composed of a plurality of like shingles arranged in courses to form a desired figure, the non-homologous edges of said shingles being laid in substantially abutting relation, each shingle having a projecting portion extending from the intersection of two adjacent edges and a stepped portion extending from the intersection of two opposite adjacent edges, said projecting portion and said stepped portion cooperating to form a slot, a slit in the main body portion of the shingle adjacent said projecting portion and a projecting lug on the lower corner of each shingle adapted to lock with said slit and said slot to secure the lower end of the shingle.

4. A roof composed of a plurality of like shingles arranged in overlapping courses to form a desired figure, the non-homologous edges of said shingles being laid in substantially abutting relation, each shingle having a projecting portion extending from the intersection of two adjacent edges and a stepped portion extending from the intersection of two opposite adjacent edges, said projecting portion and said stepped portion cooperating to form a slot, said slot lying at right angles to the line of the horizontal course of shingles, a slit in the main body portion of the shingle adjacent said projecting portion, said slit being parallel to said slot, and a projecting lug on the lower corner of each shingle, said lug of the shingles of the upper course being arranged to lock with said slit and slot of a pair of underlying shingles to secure the lower ends of said shingles of said upper course.

50 In witness whereof, I hereunto affix my signature.

NORMAN P. HARSHBERGER.
